UNITED STATES PATENT OFFICE.

ROBERT GOLDE, OF BROOKLYN, ASSIGNOR TO THE ROYAL METAL MANUFACTURING COMPANY, OF NEW YORK, N. Y.

DESIGN FOR A FRAME, &c.

SPECIFICATION forming part of Design No. 22,657, dated August 1, 1893.

Application filed June 24, 1893. Serial No. 478,754. Term of patent 3½ years.

To all whom it may concern:

Be it known that I, ROBERT GOLDE, a subject of the Emperor of Germany, residing at Brooklyn, in the county of Kings and State of New York, have invented and produced a new and original Design for Frames and the Like, (Case A) of which the following is a specification, reference being had to the accompanying drawings, forming part thereof.

- Figure 1 is a plan view of my design adapted for plaques, one-half (the lower) of which is shown in outline, the other half (the upper) showing the surface ornamentation, Fig. 2, a side elevation of the same.
- My design consists in a border comprising the bars 1 having a surface ornamentation simulating the bark of a tree, the ends of which are crooked as shown at 2, the crooks being interlaced and crossing each other at the corners of the design, the border being

disposed in rectangular form. Between the interlacing crooks lies a twig of oak leaves as at 3 from which extend acorns 4 which lie on the bark, and intertwined about the interlacing crooks of the border is a vine as at 5 25 having lily-like flowers 6, and leaves 7. These three elements are combined so as to present to the eye the combined effect of an oak branch, leaves, and acorns with an interlacing or intertwined creeping and flowering vine. 30

Having thus described my design, I claim—
The design for frames, and the like, substantially as herein shown and described.

Signed at the city, county, and State of New York this 9th day of June, 1893.

ROBERT GOLDE.
